US00D998637S

(12) **United States Design Patent** (10) **Patent No.:** **US D998,637 S**
Eirinberg et al. (45) **Date of Patent:** **** Sep. 12, 2023**

(54) **DISPLAY SCREEN OR PORTION THEREOF WITH A GRAPHICAL USER INTERFACE**

(71) Applicant: **Snap Inc.**, Santa Monica, CA (US)

(72) Inventors: **Dylan Shane Eirinberg**, Venice, CA (US); **Kyle Goodrich**, Venice, CA (US); **Andrew James McPhee**, Culver City, CA (US); **Daniel Moreno**, Los Angeles, CA (US)

(73) Assignee: **Snap Inc.**, Santa Monica, CA (US)

(**) Term: **15 Years**

(21) Appl. No.: **29/788,109**

(22) Filed: **Mar. 16, 2021**

(51) LOC (14) Cl. **14-04**

(52) U.S. Cl.

USPC **D14/486**; D14/489

(57) **CLAIM**

The ornamental design for a display screen or portion thereof with a graphical user interface, as shown and described.

DESCRIPTION

The FIGURE is a front view of a display screen or portion thereof with a graphical user interface, showing our new design.

The broken lines illustrate unclaimed portions of the display screen, and the broken lines form no part of the claimed design.

1 Claim, 1 Drawing Sheet
